UNITED STATES PATENT OFFICE

HARRY ORVILLE BLACK, OF ST. LOUIS, MISSOURI

ATTACHMENT FOR WATCH CHAINS

Application filed March 21, 1929. Serial No. 348,801.

This invention relates to an attachment for watch chains, and more especially to an attachment whereby the chain may be suspended from a belt, vest, or from the button hole 5 in the coat lapel, or any part of a garment whereby a button hole is used to hold the chain, and it is desired by the wearer to so wear the watch.

The primary object of this invention is to 10 provide an improved means whereby one end of a watch chain, may be suspended from the coat lapel, or from any part of the garment where a button hole is available, or if desired upon the belt of the wearer, without 15 in any way altering the construction of the attachment.

Another very important object of my invention is to provide a device of this character which is economical, handy and very simple to operate.

The above and numerous other objects of the invention will be apparent during a study of the following description taken in connection with the accompanying drawings, where- 25 in:

Figure is a plan view with parts broken away showing my improved watch chain attachment.

Figure 2 is a transverse sectional view taken on line 2—2 of Figure 1.

With attention directed to the drawing more in detail, it will be seen that my improved attachment comprises an elongated bar 5, the opposite ends of which are bent as 35 at 8—8, to provide a pair of inwardly extending ends 6—6 which terminate in spaced relation as clearly shown in Figure 1. Each of the ends 6—6 of the bar 5 is provided with a longitudinally extending bore 7 of relatively 40 small diameter, and are adapted to receive the laterally projecting pins 8—8 projecting from adjacent the open end 9 of a ring 10 which is adapted to be disposed intermediate the ends 6—6 of the bar 5. The projections 45 8' fit within the bore 7 in a manner loose enough to permit a movement of the ring 10 when desired. There is also provided a ring 11 which is loosely carried by the bar 5 for a purpose to be hereinafter set forth.

50 In use, one end of a watch chain, not

shown, may be linked or otherwise fixed to the ring 11, and the bar 5, formed as described so as to provide an elongated loop, may be positioned through the hole in a coat lapel or in any button hole from which it is 55 desired to suspend the watch chain, in a manner conventional to the ordinary bar used on a watch chain for this purpose. However, when it is desired to use the attachment in a manner similar to many devices now in use 60 for attaching the chain to the belt of a wearer, the wearer can simply and conveniently pass the belt through the elongated loop formed by the bar 5 and the ring 11 placed at either end of the bar to permit sufficient play 65 of the watch chain, when the watch is placed within the watch pocket of the trousers.

When the bar is inserted through the hole formed in the coat lapel, or through any button hole formed in the wearer's apparel, 70 the ring 11 is preferably placed within the ring 10, as shown in Figure 1, since the bar 5 extends for a sufficient distance from either side of the ring 10 to insure the prevention of the bar 5 from slipping through the 75 hole in the lapel or button hole.

It is also apparent that if the bar 5 be placed on the belt with the ring portion 10 being disposed inwardly toward the body of the wearer, the ring 10 may be turned so as 80 to lie flat against the inner face of the belt, and in this way will inconvenience the wearer in no manner whatsoever.

Heretofore, many separate attachments 85 for chains have been provided, but these attachments have been provided for one purpose, namely, either as an attaching means for fastening the watch chain to a belt, of which there are many known devices now in use, or in the provision of an elongated bar 90 adapted to be attached to the end of the chain for suspending the chain on the coat lapel or button hole, whereas my improved attachment can be used for either one of 95 these purposes, and from the foregoing description it will be seen that my attachment will be thoroughly reliable and efficient in use in either of these capacities. While I have herein shown and described the preferred embodiment of my invention, it is 100

to be understood, however, that minor changes in shape, size, and materials, coming within the field of invention claimed may be resorted to if desired.

Having thus described the invention, what I claim as new and desire to secure by Letters Patent is:—

1. In a new article of manufacture, an attaching bar bent to provide an elongated loop, the opposite ends of said bar terminating in spaced relation, an open ended ring adapted for engagement with a watch chain, cord or the like pivotally mounted between said ends, and a second ring loosely carried by the loop and engageable with said first mentioned ring.

2. In a new article of manufacture, comprising an elongated bar adapted for use with a watch chain, and said bar having its opposite ends bent inwardly toward each other and terminating in spaced relation, a longitudinally extending bore formed in each of said ends, a ring, projections extending laterally from the ring, and adapted to enter the bore in each of the respective ends of said bar.

3. A new article of manufacture, comprising an elongated bar adapted for use with a watch chain, and said bar having its opposite ends bent inwardly toward each other and terminating in spaced relation, a longitudinally extending bore formed in each of said ends, a ring having an opening formed therein, pins extending laterally from the ring adjacent said opening, and adapted to enter the bore formed in each of the adjacent ends of said bar, and a ring loosely carried by said bar.

In testimony whereof I affix my signature.

45 HARRY ORVILLE BLACK.
